UNITED STATES PATENT OFFICE.

ROBERT C. LANPHIER, OF SPRINGFIELD, ILLINOIS, ASSIGNOR TO SANGAMO ELECTRIC COMPANY, OF SPRINGFIELD, ILLINOIS, A CORPORATION OF ILLINOIS.

CIRCUIT-BREAKER.

1,052,595.

Specification of Letters Patent. Patented Feb. 11, 1913.

Application filed March 22, 1911. Serial No. 616,204.

To all whom it may concern:

Be it known that I, ROBERT C. LANPHIER, a citizen of the United States, residing at Springfield, in the county of Sangamon, 5 State of Illinois, have invented certain new and useful Improvements in Circuit-Breakers, of which the following is a specification, reference being had to the accompanying drawings.

10 This invention relates to circuit breakers for electric circuits of either the shunt trip coil type, the overload type, or combinations of both, and it has for its object to improve the construction and operation of devices of 15 this sort. The means by which I have accomplished this object are illustrated in the drawings and hereinafter specifically described.

That which I believe to be new is set 20 forth in the claims.

In the drawings:—Figure 1 is a central vertical section through a circuit breaker of a shunt trip coil type, with the parts in position for the passage of a current. Fig. 2 25 is a similar view with the parts in position to prevent the passage of a current. Fig. 3 is a section on line 3—3 of Fig. 1. Fig. 4 is a top or plan view, partly in section. Fig. 5 is a diagrammatic view, showing the 30 connections of the type of circuit breaker shown in Figs. 1 to 4. Fig. 6 is a diagrammatic view, showing the connections of an overload type of circuit breaker.

Referring to the several figures of the 35 drawings, in which corresponding parts are indicated by like reference characters,—10 indicates a shell of non-magnetic metal, and 11 a shell of steel or iron, about which shells is wound a coil 12, the whole being in- 40 cased in a shell 13 of steel or iron.

14—15 indicate steel or iron heads suitably joining the ends of the shell 13 with the outer ends of the shells 10—11, respectively.

45 16 indicates an iron or steel sleeve screw-threaded into the lower end of the shell 10, provided on its lower end with a graduated scale 17.

18 indicates a pointer secured to the head 50 14 and suitably positioned relative to the scale 17.

19 indicates a set-screw threaded into a

lug 20 and bearing at its inner end upon the sleeve 16 whereby it is capable of clamping the sleeve 16 in any adjusted position, 55 as will be readily understood.

21 indicates a contact connected with one end of the coil 12, and 22 indicates a binding screw connected with the other end of said coil. 60

23 indicates an iron or steel sleeve slidably mounted inside of the shells 10—11 above the sleeve 16.

24 indicates brackets mounted diametri- 65 cally opposite each other in the shell 10 and extending through slots 25 in the sleeve 23.

26 indicates a cam ring on the inner sur- 70 face of the sleeve 23.

27 indicates pins extending from the in- 70 inner surface of the sleeve 23 at its lower end.

28 indicates levers pivoted on the inner 75 ends of the brackets 24, each lever bearing at its upper end a roller 29 and at its lower end a roller 30.

It will be seen that the coil 12 is entirely 75 ironclad except for the air-gap between the slidable sleeve 23 and the adjustable sleeve 16. It will therefore be understood that when a current is passed through the coil 12 there will be a strong attraction between 80 the sleeves 16 and 23, the force of that attraction depending upon the size of the air-gap, this being regulated by adjusting the sleeve 16 up or down so that the pointer will stand at one or another point along the 85 scale 17. This scale is graduated to indicate the strength of current necessary through the coil 12 to pull down the sleeve 23 for different positions of the sleeve 16.

31 indicates a rod slidably mounted in the 90 lower end of the sleeve 16.

32 indicates a coiled spring bearing at its lower end on the sleeve 16 and at its upper end on a washer 33 carried by the rod 31, the spring thus tending yieldingly to sup- 95 port said rod 31 in its uppermost position with the washer 33 in contact with the pins 27 and with the lower ends of the slots 25 bearing against the brackets 24.

34 indicates a circumferential shoulder on 100 the rod 31.

35 indicates springs of any suitable type carried by and bearing on the levers 28 tend- 100 ing yieldingly to hold their lower ends out

- 2 away from the rod 31, and therefore tending to hold the rollers 29 in against said rod. As shown in Fig. 1, when the rod 31 is in its lowered position, the rollers 29 rest against the rod 31 above the shoulder 34, being held yieldingly in this position by the spring 35 and thus holding the rod 31 against rising. When, however, the cam ring 26, against which the rollers 30 bear, is forced downward with the sleeve 23, the rollers 30 ride up the cam 26 against the force of the spring 35, releasing the rollers 29 from the shoulder 34 and permitting the spring 32 to force upward the rod 31. This movement quickly brings the washer 33 into contact with the pins 27, stopping the downward movement of the sleeve 23 and forcing said sleeve to its uppermost position again with the rollers 30 in contact with the lower surface of the cam 26 as in Fig. 1, but with the rollers 29 in contact with the rod 31 below the shoulder 34 instead of above it as they were before the sleeve 23 was forced downward.
- 25 Coming now to the circuit making and breaking devices proper, (see Figs. 1 and 2), 36-37 indicate two oppositely-located plates provided with binding posts 38-39, respectively. Said plates 36-37 are bored 80 out concentrically, as shown in said figures, providing between them a flaring opening 40.
- 41 indicates a conical-shaped plug mounted on the rod 31 in position to close the gap 85 between the plates 36-37 when the rod 31 is in its lowered position. The plug 41 is formed of metal, preferably of a plurality of thin sheets of metal provided with radial slots 42 extending in from the periphery of 40 the plug. By reason of this construction, the plug is capable of being pressed firmly into position in the opening 40 to make a good electrical connection between the plug and the plates 36-37, the thin sheets of 45 metal being adapted to give at one point while still making a good contact at another point.
- 43-44 indicate contact brushes formed of high-resistance metal, extending from opposite sides of the plug 41, adapted normally to extend downward to make contact with small plates 45-46 before the plug 41 reaches its seat in the opening 40, and adapted when the rod 31 is forced upward 55 to continue an electrical connection between the plates 36-37 after the plug 41 has left its seat. The plates 45-46 are to be formed of high-resistance material.
- 47 indicates an arm extending from the 60 rod 31, provided on its outer end with a contact 48 adapted to engage the contact 21 when the rod 31 is lowered.
- 49 indicates a wire connecting the contact 48 with the plug 41.
- 65 In Fig. 5, the circuit breaker as just described is shown connected up in a circuit connecting a generator 50 and a storage battery 51 by lead wires 52-53. The coil 12 is shown connected up across the main circuit by a wire 54 in parallel with the storage battery 51, said secondary or shunt circuit 54 including a meter 55 of any appropriate pattern. This meter is preferably to be permanently connected up in the circuit with the storage battery and the circuit breaker for the purpose of measuring the current both on charge and discharge of the battery, the indicating hand 56 being adapted to advance more rapidly in proportion to the current passing through the meter on 70 discharge than it does on charge to compensate for the energy lost by the battery. The construction of the meter to meet this requirement is not shown, since it is well-known in the art, nor are the wires for carrying the current to be measured by the meter shown in connection therewith, the circuit 54 being only for the purpose of breaking the circuit as hereinafter described when the storage battery is fully charged or 75 when it reaches substantially a discharged condition, at either of which times the circuit 54 is adapted to be completed by the hand 56, as will be readily understood.
- With the generator 50 charging the storage battery 51 as shown in Fig. 5, with the circuit 54 through the meter 55 incomplete but with the contacts 48 and 21 in engagement, the hand 56 will continue to advance until the battery is fully charged. At that moment, the circuit 54 will be closed and a current will pass through the coil 12, causing the sleeve 23 to be immediately attracted and pulled downward by the sleeve 16. As before described, this serves to release the 80 rod 31, which is forced upward by the spring 32, thus breaking the circuit through the coil 12, as well as disconnecting the storage battery from the generator. Since the attraction between the sleeves 23 and 16 is thus taken away at the beginning of the upward movement of the rod 31 and before the washer 33 comes into contact with the pins 27, the spring 32 is able to force the rod 31 to its uppermost position, carrying 85 with it the sleeve 23, the movement ending with the parts in the positions shown in Fig. 2. The brushes 43-44 of high resistance metal serve to take up the break of the current when the plug 41 leaves its seat.
- When the battery is connected up to discharge, the rod 31 may be pushed downward, the rollers 29 riding up the shoulder 34. This of course turns the levers 28 but does not turn them sufficiently to permit the cam ring 26 to pass the rollers 30, so that when the rod 31 has reached its lowermost position with the plug 41 again closing the gap between the plates 36-37 the parts will 90 have resumed the positions shown in Fig. 1, 95

with the rollers 29 above the shoulder 34 and with the rollers 30 below the cam ring 26. When thereafter the indicating hand 56 again completes the circuit 54, either when the battery is substantially completely discharged or at any other predetermined point in the discharge of the battery, the circuit breaker acts exactly as has been described in connection with the charging of 10 the battery, coming to rest with the parts in the positions shown in Fig. 2.

In Fig. 6 is shown a slight modification of the device shown in the other figures, the modified form of circuit breaker being 15 shown connected up in series in a circuit adapted to cause a break whenever for any reason the current exceeds a certain predetermined maximum strength. In this modified form, the arm 47 and contact 21 are 20 omitted, the plate 37 being connected directly with one end of the coil 12, the other end of which is connected with the feed wire 52. In the modified construction as shown 25 in Fig. 6, the sleeve 16 is of course first adjusted to regulate the air-gap between the sleeves 16 and 23. This adjustment of the sleeve 16 regulates the strength of the attraction between the sleeves 16 and 23 for 30 any given current flowing through the coil 12. The sleeve 16 is adjusted down or up according as it is desired that a large or a small current shall be necessary for overcoming the force of the spring 35, the adjustment necessary being indicated by the 35 scale 17. When the sleeve 16 is properly set, it is clamped in position by means of the set-screw 19. Whenever thereafter the current reaches or exceeds the predetermined maximum strength desired and 40 becomes sufficient to overcome the spring 35 by means of the attraction between the sleeves 16 and 23, the sleeve 23 is pulled down, releasing the rod 31 as before described, and leaving the parts again in the 45 positions shown in Fig. 2. By this means any excessive overload of current is prevented from flowing through the work long enough to cause damage and the possible short-circuiting of delicate machinery is 50 prevented. When after the cessation of the overload current the rod 31 is again pushed down to its lowered position, the circuit is again completed ready for the starting of the machinery beyond the circuit breaker. 55 If the rod 31 is pulled down before the overload current has ceased and the circuit is then completed beyond the circuit breaker, the result will be, of course, the immediate breaking of the circuit again by the action 60 of the sleeve 23 as just described.

While I have shown the plug 41 as being electrically unconnected with each of the plates 36-37, I do not wish to restrict myself to that construction, except as herein- 65 after specifically claimed, since any con-

struction may be employed by reason of which the rising of the plug causes a break in the circuit.

What I claim as my invention and desire to secure by Letters Patent is,—

1. In a circuit-breaker, the combination of 70 a coil, a core slidably mounted in said coil and adapted to be moved therein by the passage of an electric current through said coil, a switch, a spring tending to open said switch, and a latch mounted adjacent to said slidable core adapted to hold said switch against opening, said core being provided with a cam adapted to engage and release said latch upon a full movement of said core.

2. In a circuit-breaker, the combination of 75 a coil, a core slidably mounted in said coil and adapted to be moved therein by the passage of an electric current through said coil, a switch, a spring tending to open said switch, and a latch mounted adjacent to said slidable core adapted to hold said switch against opening, said core being provided with a cam adapted to engage and release 80 said latch upon a full movement of said core whereby said spring is permitted to open said switch, the opening of the switch by said spring also having the effect of restoring said cam to operative engagement with said latch.

3. In a circuit-breaker, the combination of 85 a coil, a soft-iron sleeve slidably mounted in said coil and adapted to be moved therein by the passage of an electric current 100 through said coil, a switch, a spring tending to open said switch, and a latch adapted to hold said switch against opening, said sleeve being provided with a cam on its inner surface adapted to engage and release 105 said latch upon a full movement of said slidable sleeve.

4. In a circuit breaker, the combination of 110 a coil, a spring-seated rod extending into said coil, a block secured on said rod by the movement of which an electric circuit is broken, a shoulder on said rod, a lever engaging said shoulder and preventing the rising of said rod and block, and a core slidably mounted in said coil and adapted to be 115 moved therein by the passage of an electric current through said coil, said core being provided with a cam which operatively engages said lever whereby upon the movement of said core said lever is disengaged 120 from said shoulder.

5. In a circuit breaker, the combination of 125 a coil, a spring-seated rod extending into said coil, a block secured on said rod by the movement of which an electric circuit is broken, a shoulder on said rod, a lever engaging said shoulder and preventing the rising of said rod and block, a core slidably mounted in said coil and adapted to be moved therein by the passage of an electric current 130

through said coil, said core being provided with a cam which operatively engages said lever whereby upon the movement of said core said lever is disengaged from said shoulder permitting said rod and block to rise, and means actuated by said spring as said rod rises to return said core into operative engagement with said lever.

6. In a circuit breaker, the combination of 10 a coil, a spring-seated rod extending into said coil, a block secured on said rod by the movement of which an electric circuit is broken, a shoulder on said rod, a lever engaging said shoulder and preventing the 15 rising of said rod and block, a core slidably mounted in said coil and adapted to be moved therein by the passage of an electric current through said coil, said core being provided with a cam which operatively engages 20 said lever whereby upon the movement of said core said lever is disengaged from said shoulder permitting said rod and block to rise, means actuated by said spring as said rod rises to return said core into operative 25 engagement with said lever, and a spring adapted to hold said lever yieldingly in operative position, whereby upon the pushing down of said rod said lever is adapted to again engage said shoulder and hold said 30 rod against rising.

7. In a circuit breaker, the combination of a coil, a rod extending into said coil, a block secured on said rod by the upward movement of which an electric circuit is broken, 35 a shoulder on said rod, a pair of levers pivotally mounted on opposite sides of said rod in said coil, and adapted to engage said shoulder to prevent the upward movement of said rod and block, a magnetic sleeve slidably mounted in said coil and adapted to 40 be moved downward by the passage of an electric current through said coil, a cam ring on the inside of said sleeve operatively engaging said levers whereby upon the downward movement of said core said levers are 45 disengaged from said shoulder, a spring adapted to raise said rod when released by said levers, and means carried by said rod adapted to engage said sleeve returning it 50 to its normal position with the cam again in operative engagement with said levers.

8. In a circuit-breaker, the combination of a coil, a sleeve of magnetic material fixed in the upper end thereof, a non-magnetic sleeve 55 fixed in the lower portion thereof, a third sleeve of magnetic material adapted to slide in said coil with its upper end in contact with said first-named sleeve and with its lower end in contact with said second-named 60 sleeve, a core in the lower end of said second-named sleeve, a spring-seated block by

the movement of which an electric circuit is broken, and a lever pivotally mounted in said coil adapted to hold said spring-seated block against movement, said third sleeve 65 being provided with a cam adapted to engage said lever to release it from said spring-seated block upon the movement of said sleeve toward said core.

9. In a circuit-breaker, the combination of 70 a coil, a sleeve of magnetic material fixed in the upper end thereof, a non-magnetic sleeve fixed in the lower portion thereof, a third sleeve of magnetic material adapted to slide in said coil with its upper end in contact 75 with said first-named sleeve and with its lower end in contact with said second-named sleeve, a core in the lower end of said second-named sleeve, a rod extending into said coil by the upward movement of which an 80 electric circuit is broken, a lever pivotally mounted in said coil, when said rod is in its lowermost position said lever extending at its upper end above and engaging a shoulder on said rod and extending at its lower end 85 below and engaging a cam on the inside of said third sleeve, and a spring adapted to force said rod upward when said lever is released from said rod by the swinging of the lever due to the downward movement of said 90 third sleeve.

10. In a circuit-breaker, the combination of a coil, a sleeve of magnetic material fixed in the upper end thereof, a non-magnetic sleeve 95 fixed in the lower portion thereof, a third sleeve of magnetic material adapted to slide in said coil with its upper end in contact with said first-named sleeve and with its lower end in contact with said second-named sleeve, a core in the lower end of said 100 second-named sleeve, a rod extending into said coil by the upward movement of which an electric circuit is broken, a lever pivotally mounted in said coil, when said rod is in its lowermost position said lever extending at 105 its upper end above and engaging a shoulder on said rod and extending at its lower end below and engaging a cam on the inside of said third sleeve, a spring adapted to force said rod upward when said lever is released 110 from said rod by the swinging of the lever due to the downward movement of said third sleeve, and means carried by said rod adapted to engage said third sleeve as said rod is moved upward by said spring and to raise 115 said sleeve again into normal position with its cam above the lower end of said lever.
